UNITED STATES PATENT OFFICE.

CHARLES E. WILCOX, OF ANAHEIM, CALIFORNIA, ASSIGNOR TO E. C. WILSON, OF LOS ANGELES, CALIFORNIA.

WELL-PIPE ELEVATOR.

Application filed January 29, 1921. Serial No. 440,933.

To all whom it may concern:

Be it known that I, CHARLES E. WILCOX, a citizen of the United States, residing at Anaheim, in the county of Orange, State of California, have invented certain new and useful Improvements in Well-Pipe Elevators, of which the following is a specification.

This invention has to do with elevators of the character used for handling casings or pipes in oil and water wells, etc., and it is an object of the invention to provide a simple, strong and effective device of this character.

It is an object of the invention to provide an elevator presenting no projecting or weak parts, which can be lighter in construction than an ordinary elevator for a given strength, and in which the casing encircling structure is subjected to minimum strain.

A noteworthy feature of the invention is the general arrangement and formation of the device. The link parts of the device support the casing engaging structure at, or immediately adjacent, the casing engaging part of such structure, thereby causing the centers of support to be close to the center of the load. With the centers of support close to the center of load, there is very little leverage action in the casing engaging structure tending to break or open it. Further, by the arrangement and formation of the device the links are securely and effectively held in the proper engagement with the casing engaging structure during operation and handling of the device, but are easily and quickly removable or detachable from the casing engaging structure upon being manipulated in a certain manner and without the necessity of detaching or removing any additional part or parts.

The various objects and the corresponding features and advantages gained by the carrying out of said objects will be best and most fully understood from the following detailed description of a typical embodiment of the invention, throughout which reference is had to the accompanying drawings in which:

Fig. 1 is a plan section of the elevator taken immediately above the casing engaging structure as indicated by line 1—1 on Fig. 2; Fig. 2 is a side elevation of the device, being a view taken as indicated by line 2—2 of Fig. 1 and showing the transverse curvature of the end portions of the links; Fig. 3 is a

side elevation of the casing engaging structure only, viewed as indicated by line 3—3 on Fig. 1; and Fig. 4 is a side elevation of the device, being a view taken as indicated by line 4—4 on Fig. 1 and showing the longitudinal curvature of the end portions of the links.

Throughout the drawings numeral 10 designates the casing engaging structure which is adapted to be supported by a pair of bails or links 11. The structure 10 has a longitudinal opening 31 adapted to receive a casing. The links 11 are connected to the structure 10 by being arranged in notches 12 formed in the sides of the structure 10. In the preferred form of the invention two links 11 are employed to support the structure 10 and the notches 12 to carry the links are arranged diametrically opposite each other in the sides of the structure 10.

As far as the present invention is concerned, the structure 10 may be of any general design and construction; for instance it may be solid or sectional. The particular structure 10 illustrated in the drawings, which is a typical structure presented to facilitate a clear understanding of the invention, comprises two parts A and B. The parts A and B fit together or cooperate to form a clamp adapted to embrace or encircle a casing. It may be here stated that when I use the term "casing" I mean to include also pipe or any object or objects possessing or having the general characteristics of casing or pipe. The parts A and B are hinged together at one end by a vertical hinge pin 13; the other ends being free to swing to open and close the elevator, or structure. The means provided for holding the free or swinging ends of the parts A and B together when the structure 10 is closed, or set, around a casing, comprises, generally, a T-shaped latched part 14 mounted on the part A to cooperate with lugs 40 provided on the part B. The latch 14 is carried on a rod 15 supported in lugs 16 on the part A. A spring 17 is arranged in connection with the rod 15 to tend at all times to move the latch 14 inwardly, as indicated by the arrow in Fig. 1. The general construction is set forth and claimed in Patent No. 1,314,996 issued to Elihu C. Wilson on September 2, 1919, and an application of Elihu C. Wilson entitled "Well elevators," filed April 20, 1920, Serial Number 375,332.

110

In the particular structure shown in the drawings, means is provided for positively locking the parts A and B together in the set position so that they cannot under any circumstances become separated when the elevator is in operation. A recess 18 is formed in the part B and a lug 19 is formed on the latch 14 to extend into the recess 18 when the latch is closed. An opening 20 extends vertically downwardly through the part B, opening into the recess 18, and a like opening 21 is formed in the lug 19 to register with the opening 20 when the lug is in place in the recess. A rod 22 is slidably carried in the opening 20 and extends from the upper end of the opening, carrying at its upper end a head 23 adapted to seat in recesses 24 formed in the parts A and B. The head 23 is formed at its ends with downwardly extending lugs 25 adapted to extend into notches 26 provided in the recesses 24. A spring 27 is arranged in connection with the rod 22 and head 23 to normally hold the rod in the position shown in Fig. 2 of the drawings. When the rod 22 is in this position its lower end is within the opening 20 and the head 23 is completely out of the recess 24. When the elevator is arranged on the casing and is lifted the head 23 engages the collar of the casing, is forced downwardly into the recess 24, the lugs 25 on the head 23 are moved into the notches 26, and the lower end portion of the rod 22 is moved downwardly into the opening 21 in the lug 19. The parts A and B are then positively locked together by the cooperation of the lugs 25 and notches 26 and also by the cooperation of the rod 22 and lug 19. The particular construction just described is set forth in detail and is claimed in my copending application entitled "Lock for well casing elevators", filed on even date herewith and bearing Serial Number 440,932.

All the links 11 and the openings, or notches, 12 being structurally the same and each of the links being adapted to cooperate with a notch in the same manner, I will proceed to describe in detail one of the notches, one of the links, and the manner in which a notch and link cooperate. It is to be understood, of course, that such description applies equally to all of the notches and links.

A vertically disposed rib or projection 30 extends radially outwardly from the side of the structure 10, and in the particular case herein set forth from the side of one of the parts of structure 10 between its ends, as clearly shown throughout the drawings. The notch 12 extends inwardly and upwardly through the projection 30 and into the structure 10, proper, to the opening 31 in the structure 10. The outer portion 33 of the notch 12 is diagonally disposed across

the projection 30 and extends upwardly and inwardly through the notch 30 to the inner portion 35, of the notch, which is somewhat enlarged, as clearly shown in the drawings. The inner portion 35 of the notch extends transversely of the longitudinal axis of the structure 10, is substantially round in cross sectional configuration, and has rounded edges 36. With the outer portion 33 of the notch formed diagonally through the projection 30, there is formed a downwardly projecting part 41 and an upwardly projecting part 42. The projecting parts 41 and 42 are on opposite sides of the outer portion 33 and at opposite sides of the projection 30, and the vertical distance between the ends of said projecting parts is considerably less than the distance between the two sides of the outer portion 33 of notch 12 and the thickness of the link 11.

The bail or link 11 is in the form of a continuous elongated loop having substantially straight side parts 50, a curved upper end part 51 connecting the upper ends of the side parts 50 and a curved lower end part 52 connecting the lower ends of the side parts 50. The upper end part 51 is adapted to receive a hook, or like device, while the lower end part 52 is adapted to be carried in the inner portion 35 of notch 12. In accordance with the present invention the lower end part 52 is evenly longitudinally curved between the ends of the side parts and is also transversely curved, preferably only in one direction, as clearly shown in Figs. 1 and 2 of the drawings. At some part or parts of the link other than the curved end part 52, the cross section of the link is reduced. For instance, at the side part 50 the link may have flattened portions 60.

To arrange the link 11 in the notch 12 the reduced part of the link, that is the part where the link is flattened, is arranged at the outer end of the outer portion 33 of notch 12 and the link is tilted bodily to a position where it is in line with the outer portion 33 of the notch 12. From this position the reduced portion of the link may be moved through the outer portion 33 of the notch 12 into the inner portion 35. The inner portion 35 being enlarged, that is, being larger than the outer portion 33, the links can be easily moved longitudinally until the end part 52 is within the inner portion 35, as clearly shown throughout the drawings. It will be particularly noted that the rounded edges 36 of the portion 35 conform to the longitudinal curvature of the end part 52 and that the link is arranged so that the end part 52 curves transversely inwardly toward the center of the device. The inner portion 35 of the notch 12 is sufficiently large to carry the end part 52 of the link with more or less clearance so that it can move or swing the 120

necessary amount. With the link thus arranged in the notch it is obvious how it will not become displaced therefrom under ordinary working and handling conditions and even after it has worn considerably. This is true not only because the end portion 33 of the notch is only sufficiently wide to pass the reduced portion of the link, but also because the vertical distance between the projecting parts 41 and 42 is very much less than the size of any part of the link, even the reduced portion of the link. The only way in which the link can become displaced from the notch 12, or can be removed from the notch 12, is to move it longitudinally around in the notch until the reduced portion is in the notch, whereupon it can be removed by tilting it to be in line with the end portion 33 of the notch.

From inspection of the drawings it will be readily seen that the link 11 engages or supports the structure 10 at a point immediately adjacent the opening 31 of the structure 10, thereby causing the point of support to be as close as possible to the center of the load supported by the structure 10. Further, from inspection of the drawings, it will be readily seen how the longitudinal and transverse curvature of the end parts 52 and the links, causes the links to engage the structure 10 immediately adjacent the opening 31 in the structure 10 and yet extend outwardly and upwardly from that point without touching or engaging any other parts of the structure 10.

In practice it is preferred that the notches 12 be arranged diametrically opposite each other in the structure 10 and that they be located vertically in the structure 10 so that the inner portions 35 are slightly below the center of the structure 10. With this location of the notches, and the above described cooperation between the notches and links to cause the points of support to be as close as possible to the center of load the strains in the structure 10, tending to break or pull it apart, are reduced to a minimum. For this reason the structure provided for connecting and holding together the parts of the structure 10 can be made considerably lighter than in ordinary devices of this character. Further, by the arrangement and construction hereinabove set forth there are no large heavy projections or lugs for carrying the links 11, and no retaining or locking devices to hold the lugs in place to support the links and of retaining devices for the links, the elevator can be made lighter and neater than has heretofore been possible.

The following claims are directed to the feature of the supporting links being positioned closely under the load—in openings that extend into the elevator body wall; and the combination of such feature with the feature of link removal. In a divisional appli-

cation Ser. No. 642,149, filed May 28th, 1923, entitled "Well pipe elevator," I have claimed the feature of link or bail removal in itself.

Having described a preferred form of my invention, I claim:

1. In a device of the character described, a structure having a longitudinal opening to receive a casing and a notch extending upwardly and inwardly in its side to the opening, and a supporting link carried in the inner part of the notch.

2. In a device of the character described, a structure having a longitudinal opening to receive a casing and notches at opposite sides extending inwardly to the opening, and supporting links carried in the inner parts of the notches.

3. A link for supporting a casing engaging structure, having the part which engages the structure curved longitudinally and transversely.

4. A link for supporting a casing engaging structure, having the part which engages the structure curved longitudinally and transversely inwardly.

5. In a device of the character described, a supporting link, a structure having a longitudinal opening to receive a casing and a notch extending upwardly and inwardly in its side to the opening, the notch having an enlarged transversely disposed inner part adapted to carry the link and a diagonal outer part, and a reduced part in the link adapted to be passed through the outer part of the notch when in line with said part of the notch, said reduced part being the only part of the link passable through the outer part of the notch.

6. In a device of the character described, a supporting link, a longitudinally and transversely curved part in the link, a reduced part in the link, and a structure having a longitudinal opening to receive a casing and a notch extending upwardly and inwardly in its side to the opening, the notch having an enlarged transversely disposed part adapted to carry the curved part in the link and a diagonally disposed contracted outer part adapted to allow passage of the reduced part when said part is in line with it, said reduced part being the only part of the link passable through the outer part of the notch.

7. In a device of the character described, a structure having an opening to receive a casing and a notch in its side extending to the opening, and a link having a longitudinally and transversely curved part carried in the inner part of the notch.

8. A supporting link for an elevator, that has its lower part curved inwardly transversely to put that part close to the elevator relatively to the remaining portion of the link.

9. In a device of the character described,

a casing encircling body with a casing receiving opening and with bail receiving openings in the side of the body, said openings extending laterally into the body in-
6 wardly toward the casing receiving opening.

10. In a device of the character described, a casing encircling body with a casing receiving opening, and with bail receiving openings in the side of the body, said open-
10 ings extending laterally into the body in-

wardly toward the casing receiving opening; and bails with their lower ends curved inwardly to reach the inner part of said bail receiving openings.

In witness that I claim the foregoing 15
I have hereunto subscribed my name this
18th day of January, 1921.

CHARLES E. WILCOX.

Witness:

VIRGINIA BERINGER.
